United States Patent Office

Des. 224,197

Patented July 11, 1972

224,197

SEWING MACHINE CABINET

Howard Peters, Dyersburg, Tenn., assignor to U.S.
Industries, Inc., New York, N.Y.

Filed July 13, 1970, Ser. No. 23,913

Term of patent 3½ years

Int. Cl. D6—04

U.S. Cl. D6—181

Fig. 1

FIG. 1 is a front perspective view of a sewing machine cabinet embodying my new design;

FIG. 2 is a rear perspective view thereof, with the top panel extended; and

FIG. 3 is a rear perspective view thereof with the top panel closed.

I claim:

The ornamental design for a sewing machine cabinet, substantially as shown and described.
